FIG. 3

Fig. 1 is a front elevational view of a sink attached dishwasher unit embodying my new design;

Fig. 2 is a side elevational view from the right side of Fig. 1;

Fig. 3 is a side elevational view from the left side of Fig. 1, and

Fig. 4 is a top plan view of the unit.

The dominant feature of the design resides in the portions shown in full lines. The hose and brush portions have been omitted from Figs. 2, 3 and 4 for convenience of illustration.

I claim:

The ornamental design for a sink attached dishwasher unit, substantially as shown and described.
